UNITED STATES PATENT OFFICE.

WILLIAM A. GEIGER, OF CHICAGO, ILLINOIS, ASSIGNOR TO WILLIAM H. MINER, OF CHAZY, NEW YORK.

RAILWAY DRAFT-RIGGING.

1,255,153.

Specification of Letters Patent.

Patented Feb. 5, 1918.

Application filed September 5, 1916. Serial No. 118,395.

To all whom it may concern:

Be it known that I, WILLIAM A. GEIGER, a citizen of the United States, residing at Chicago, in the county of Cook and State 5 of Illinois, have invented a certain new and useful Improvement in Railway Draft-Riggings, of which the following is a full, clear, concise, and exact description, reference being had to the accompanying drawings, forming a part of this specification.

This invention relates to improvements in railway draft riggings.

The object of the invention is to provide an arrangement of friction draft gear for 15 railway cars wherein is employed a rear abutment or stop casting secured to the sills for preventing the forward movements of the friction shell.

The invention furthermore consists in the 20 improvements of the parts and devices and in the novel combinations of the parts and devices herein shown, described or claimed.

In the drawing forming a part of this specification, Figure 1 is a vertical, longitudinal central section of a draft rigging showing one embodiment of my improvements in connection therewith. Fig. 2 is a horizontal sectional view of the structure illustrated in Fig. 1 and taken on the line 25 2—2 thereof. Fig. 3 is a vertical, transverse sectional view taken substantially on the line 3—3 of Fig. 1. And Figs. 4 and 30 5 are views corresponding respectively with Figs. 1 and 3 but illustrating another embodiment of the invention, Fig. 5 being taken on the line 5—5 of Fig. 4.

In said drawing, and referring to the structure illustrated in Figs. 1 to 3, 10—10 denote channel center or draft sills of usual 40 form, 11 a draw bar, 12 a cast yoke having a hooded forward end to which the draw bar is connected by a coupler key 13 slidably mounted in suitable slots in the draft sills. Mounted within the yoke 12 is a friction draft gear of well known type designated generally by the reference A. Extending between and connected to the sills at the rear of the gear A is a heavy abutment or stop casting designated generally by the 45 reference B.

The casting B, as shown, comprises a front vertical stop face 14, parallel side walls 15—15 riveted to the sills 10, upper wall 16, reinforcing horizontal flanges 50 170—170, and a forwardly extended, pref-

erably integral arm or plate 17, the latter extending over the friction gear for the purpose hereinafter described.

The gear A, as shown, comprises a combined friction shell and spring casing 18 with the shell at the rear, springs 19, and friction elements 20, the latter bearing against the rear end of the yoke 12, the yoke in turn normally abutting the vertical face 14 of the casting B.

In buff, it is apparent that the yoke and inner element of the friction mechanism are prevented from movement by the casting B and hence as the friction shell moves rearwardly the friction gear will be actuated in the usual manner. In draft, it is necessary to prevent longitudinal movement of the shell 18 and for this purpose, the 55 arm 17 is provided at its front end with a pair of laterally spaced, depending lugs or shoulders 21—21 which coöperate with corresponding shoulders 22—22 formed in the upper face of the friction shell and spring cage.

In order to reinforce the shoulders 21, the arm 17 is provided on its under face 60 with ribs 23, 23, see Fig. 3. The gear and yoke are supported by means of a saddle plate 24 which is detachably bolted to the lower flanges of the draft sills by a sufficient number of bolts to withstand a heavy pulling strain, three of such bolts being shown in the drawing. Said saddle plate 24 is provided on its upper face with a pair of 65 upstanding lugs or shoulders 25—25, which also engage corresponding shoulders 26—26 formed on the lower face of the friction shell and spring casing 18.

The shoulders 25 are arranged opposite the shoulders 21 so that the casting 18 is engaged at four 70 points during the draft actions of the gear. It will also be noticed from Fig. 3, that the four lugs 21 and 25 form guides for the upper and lower arms of the yoke. 75

In assembling the draft rigging, the friction gear is first placed within the yoke and 80 then the yoke and gear are raised vertically, with the shoulders 22 of the casting 18 engaging behind the shoulders 21. Thereupon the saddle plate 24 is applied, thus not only supporting the parts but preventing forward movement of the friction shell.

In the construction illustrated in Figs. 4 and 5, the casting B' is quite similar to the casting B except that the arm 117 thereof is provided with a single, centrally located 110

transverse shoulder 121 on its underface which coöperates with a single upwardly extended, centrally located shoulder 122 on the friction shell 118. The shell 118 is provided on its bottom side with a corresponding depending shoulder 126 which is arranged to coöperate with a transversely extending shoulder 125 formed on the rear edge of the saddle plate 124. In this construction, a horizontal yoke 112 is employed instead of a vertical yoke and in order to support and guide said yoke, the saddle plate 124 is provided with upstanding flanges 40 near each end thereof on which the arms of the yoke reciprocate back and forth. The transverse shoulder 121 of the casting B' is suitably reinforced by longitudinally extending ribs or flanges 123. The manner of assembling the gear illustrated in Figs. 4 and 5 will be obvious from the preceding description.

I claim:

1. In a draft rigging, the combination with draft sills, of a gear including a friction shell between said sills, an abutment casting at the rear of the gear and secured to the sills, said casting having an arm extended forwardly to overlap said shell, said arm and shell having coöperating engaging shoulders arranged to prevent forward movement of the shell relatively to said casting under draft.

2. In a draft rigging, the combination with draft sills, of a gear including a friction shell between said sills, an abutment casting at the rear of the gear and secured to the sills, said casting having an arm extended forwardly to overlap said shell, said arm and shell having coöperating engaging shoulders arranged to prevent forward movement of the shell relatively to said casting under draft, and a saddle plate extending between the sills beneath the gear, said saddle plate and friction shell having coöperating engaging shoulders to prevent forward movement of the shell under draft.

3. In a draft rigging, the combination with draft sills, of a gear including a friction shell mounted between said sills, an abutment casting at the rear of the gear and secured to said sills, said casting having a forward extension over the friction shell, said extension being provided with a depending shoulder, said shell having a shoulder on its upper side engaging the first named shoulder on the rear side of the latter to thereby prevent forward movement of the shell relatively to said casting under draft, and means for supporting the shell.

4. In a draft rigging, the combination with draft sills, of a gear including a friction shell mounted between said sills, an abutment casting at the rear of the gear and secured to said sills, said casting having a forward extension over the friction shell, said extension being provided with a depending shoulder, said shell having a shoulder on its upper side engaging the first named shoulder on the rear side of the latter to thereby prevent forward movement of the shell relatively to said casting under draft, and means for supporting the shell, said means including a saddle plate extending beneath the shell, said saddle plate and shell having coöperating engaging shoulders also adapted to prevent forward movement of the shell under draft.

5. As an article of manufacture, an abutment casting adapted to be mounted between and secured to draft sills of a car, said casting having a vertical abutment face at its front end and a forwardly extending integral arm adapted to overlap a shell-like member of a draft gear, said arm having a shoulder near its front end adapted to cooperate with a shoulder of said member to prevent forward movement of the latter under draft.

In witness that I claim the foregoing I have hereunto subscribed my name this 29th day of August, 1916.

WILLIAM A. GEIGER.
